Primary Examiner — Kevin Rudzinski*Assistant Examiner* — Sean D Lough(74) *Attorney, Agent, or Firm* — Michael Best &
Friedrich LLP(57) **CLAIM**We claim the ornamental design for an air inlet damper, as
shown and described.

DESCRIPTION

FIG. 1 is a bottom perspective view of an air inlet damper
showing the new design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken lines present in all FIG. views illustrate portions
of the air inlet damper that is environment of the claimed
design and forms no part of the claimed design.**1 Claim, 6 Drawing Sheets**| (56)	References Cited
